UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,070, dated September 9, 1902.

Application filed July 29, 1902. Serial No. 117,589. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is shown in front elevation.

The leading features of my design consist in a frame the sides and top of which have plain inner and outer edges or borders. At the bottoms and tops of the sides and reversely arranged are scrollwork devices having a vase resemblance. About midway of each of the sides is a medallion, with the foils extending from its upper and lower sides. The top piece, which is in the shape of a hood, has orna-

mentations at its corner and a casket or shield like device at its center, with oppositely extending foliation and scrollwork branching therefrom. The center or summer front has as its principal ornamentation the representation of a lyre inclosed in a beaded 25 semicircular border, with garlands of flowers extending upwardly and outwardly from the base of the lyre. Below the summer front is an open-work frame having two rows of openings.

I claim—

The ornamental design for a fireplace-front as shown and described.

In witness whereof I have hereunto set my hand.

THOMAS M. DUDGEON.
